FIG. 3.

UNITED STATES PATENT OFFICE

LEON T. ELIEL, OF PASADENA, CALIFORNIA, ASSIGNOR TO ELIZABETH S. ELIEL

FOLDING MIRROR STEREOSCOPE

Application filed May 6, 1925. Serial No. 28,353.

My invention relates to stereoscopes, and more particularly to a folding mirror stereoscope.

The use of a mirror stereoscope is well known to those versed in the art, the present laboratory instrument being generally employed for examining topographical photographs for determining contours, making maps, and other adaptations involving minute inspection of photographs and illusion of relief.

Such instruments heretofore developed have been expensive, heavy and bulky, and could be conveniently used only in a laboratory.

These instruments are also subject to injury and are likely to be thrown out of adjustment when carried.

Great advantages may sometimes be gained by using a stereoscope in the field or on the location of the photographed territory. It is also often desirable to carry the stereoscope for demonstrating its utility in colleges, schools and engineering camps as well as in commercial topographical laboratories and engineering offices.

It logically follows that:

An object of the present invention is to provide a folding mirror stereoscope which is light and compact, rendering it readily portable.

A further object is to provide such a stereoscope in "knock down" or foldable form, such that it may be readily folded and packed in a small case for being carried or shipped.

A further object is to provide in such a stereoscope means for adjusting the mirrors to accommodate pupillary separation in the eyes of different individuals.

Another object is to provide in combination with a folding mirror stereoscope of the type described, a portable hair line suspension equipment, the parallel lines of which are adapted to be interposed between the mirrors and the photographs under examination to facilitate determination of contours and elevations.

Other objects and advantages will be made manifest in the following specification of an

embodiment of the invention illustrated in the accompanying drawings, in which:

Fig. 1 is a vertical front view of the stereoscope set up in position for use with the hair line suspension attachment also in place.

Fig. 2 is a plan view of the stereoscope with the hair line suspension omitted.

Fig. 3 is a front view of the stereoscope folded.

Fig. 4 is a fragmentary view partly in section of the stereoscope taken from the rear and showing the focusing arrangement.

Fig. 5 is a vertical fragmentary section through the center of the stereoscope, being taken on the line 5—5 of Fig. 2.

Fig. 6 is a view similar to Fig. 5 with the small mirrors folded as when not in use.

Fig. 7 is a plan view of the hair line suspension device.

The stereoscope as herein described comprises a supporting member 1 which may be formed of cast aluminum, or any other light and durable material. This supporting member is a substantially flat plate roughly describing a T, the vertical member 2 of which is intended to afford a part of a base upon which the stereoscope may stand. At each side of the member 2 is a triangular wing 3 which is pivotally engaged to the base and is adapted to be swung forwardly of the member 2 and perpendicular thereto so that a three-sided standard is provided, such as shown in Fig. 1.

The preferred method of pivotally engaging the wings 3 to the vertical member 2 consists in forming the contiguous edges of the related members with alternating ears 4 and recesses 5 adapted to properly register, there being a hole 6 extending through the entire length of the contiguous ears and a pin 7 being inserted therethrough.

Near the juncture of the vertical member with the horizontal member of the T a small mirror mounting and adjusting arrangement 8 is provided. This constitutes a sliding plate 9 which is adapted to face on the front of the vertical member 2 and to slide thereagainst, the plate 9 being provided with a threaded lug 10 through which an adjusting screw 11 is adapted to operate. The adjusting screw 11

is located in a rectangular recess 14 in the vertical member 2, and its ends are rotatably retained in a pair of horizontal thrust bearings 15 and 16. The screw is provided with an enlarged annular knurled portion 17 by which it may be turned. It will thus be seen that the plate 9 may be moved up or down by a rotation of the screw 11.

A pair of vertical guide bars 12 having their ends in thrust bearings 15 and 16 engage in sliding relationship a pair of collars 13 which are secured upon the back of plate 9, providing means for accurately retaining the mirror support in position when it is raised or lowered by the screw 11.

Upon the forward face of the plate 9 is hingedly mounted a supporting block 18 presenting an inverted V-shaped edge 19 which is intended to support the small mirror plates 20 and 21 in proper position. The block is formed with a substantial thickness at the V-shaped end and is reduced adjacent its hinged connection 22 with a small block 23, which is firmly secured to the plate 9.

The purpose of having the block 18 hinged at 22 is to afford means for folding the block down out of the way, as shown in Figs. 3 and 6, when the stereoscope is to be packed away.

The small mirror plates 20 and 21 are hinged the length of their contiguous edges as at 24 in a manner similar to the hinging arrangement of the base member. This manner of engaging the mirror plates will render it possible for them to lie flat when folded and to readily accommodate themselves to an angular disposition when elevated. They are carried upon a common T-shaped hinge member 27, one end of which is located at the upper end of the plate 9 and hinged thereto to permit movement of the hinge member 27 in a vertical plane whereby the mirror plates 20 and 21 are hinged relative to the supporting member 1. A pair of mirrors 28 and 29 are secured upon the upper faces of the plates 20 and 21 by any suitable means, such as by small clips 30 retained by screws 31, an edge of each clip extending over the edge of the mirror.

A pair of large mirror plates 34 and 35 are disposed at the outer ends of the supporting member cross piece, being hinged in notches formed upward from the lower edge thereof. This hinge attachment is preferably formed by means similar to those employed between the wings 3 and the member 2.

The disposition of the mirror plates 34 and 35 is diagonal with reference to the horizontal extension of the cross member so that when the plates are elevated into position for use, as shown in Fig. 1, they will extend at right angles to the member 1 and their planes will be parallel to the planes of their corresponding small mirrors.

Each large mirror plate is provided on its upper face with a small button 36 which is

adapted to be engaged by a pivoted retaining clip 37 secured to the member 1. The retaining clip comprises a small base 38 which may be screwed or otherwise fastened to the member 1, and a longitudinal extension 39 which is provided at its outer end with an angular lug 40 formed with ears which are intended to be slipped over the neck of the button 36 and be retained by the head of the button. When the retaining clips 37 are folded down out of the way the lugs 40 may be received in recesses 41 provided in the face of the supporting member 1. To the under side of each of the large mirror plates 34 and 35 is secured a mirror 44 retained in position by any suitable means such as the clips 43 herein illustrated, which are secured by screws 42 threaded into the mirror plate. Recesses 45 are provided in the edges 46 of the member 1 for the reception of clips 43 when the large mirrors are folded in position for packing.

The use of the stereoscope just described is as follows: Referring to Fig. 3, the instrument is seen as when folded for packing or transportation. To set the device up for use the wings 3 should be swung forwardly upon the pins 7 to the position shown in Fig. 1; the small mirror plates swung forwardly and upwardly on the hinge 27 and the supporting block 18 swung upwardly on the hinge 22, the small mirror plates being then lowered upon the inverted V-shaped surface presented by the block 18. The weight of the mirror plates will retain the block in upright position and the weight of each individual mirror plate will cause them to pivot upon the hinge extension 24 and to assume a relatively angular position with the mirrors 28 and 29 disposed at planes substantially perpendicular relative one to the other. The retaining clip extensions 39 should be swung outwardly from their folded position and the large mirror plates 34 and 35 elevated upon their pivotal connection with the member 1 so that the retaining clip lugs 40 may be caused to engage the buttons 36. A slight frictional relation between the retaining clips and the buttons causes them to be engaged securely, as well as the normal pressure exerted by the weight of the mirror plates. The instrument may then be focused by rotating the screw 11 to raise or lower the plate 9 upon which is mounted the small mirrors.

It should be apparent that this movement varies the vertical relationship between the complementary mirrors, the eyes of the observer, and the pictures thereby making an easy adjustment by which differences in the pupillary separation of the observer's eyes may be compensated for without moving the pictures.

An operation the reverse of that just described would obviously fold the stereoscope

into a practically flat package which may be readily enclosed in a case.

The hair line suspension arrangement adapted to be used in conjunction with the folded mirror stereoscope comprises a pair of longitudinal bars 50 and 51 which are provided at their ends with legs 52 and 53 hinged at their upper ends by hinges 54 to the under sides of the longitudinal bars so that they may be folded against the bars when it is desired to pack the device. Each leg is provided on its outer edge near the upper end with a spring clip 55, the lower end of which is firmly secured to the leg and the upper end of which describes an arc, the inner side of the arcuate portion being adapted to engage the end of the longitudinal bar and to yieldably retain the bar and leg in secure relationship. The longitudinal bars 50 and 51 are related by a central tie 56 which is pivotally secured as by rivets or screws 57 and 58 to the longitudinal bars. Small holes 59 are drilled into the longitudinal bars 50 and 51 for the purpose of receiving parallel hair lines 60 which are suspended between the bars. These hair lines may be retained in the holes provided by small wooden plugs 61.

This arrangement permits the hair line suspension device to be set up in combination with the stereoscope as shown in Fig. 1, one of the longitudinal bars being disposed adjacent the vertical member 2 above the upper ends of the wings 3. If it is desired to vary the position of the hair lines 60 with relation to the longitudinal disposition of the stereoscope or photographs under observation the second, or outward, longitudinal bar may be shifted upon the pivots 57 and 58 to cause the cross hairs 60 to traverse the images under observation in a diagonal line; the construction provided affording parallelity of the hair lines 60. The use of the hair line arrangement is fully set forth in my co-pending application for Method of and apparatus for making maps, filed May 4, 1925, Serial No. 27,712. The operation of the present device differs only in that instead of actually changing the separation between the hairs this instrument accomplishes the same end by use of the focusing screw 11. By thus raising or lowering the small mirrors the parallax between the elevated hair lines 60 causes an apparent difference in the separation as the hairs are seen projected upon the pictures below. This causes them to appear in contact with the ground at different elevations as the screw 11 is turned.

It is further possible by use of this adjusting screw to determine on the photograph the imaged points intersected by any vertical plane, regardless of differences in elevation of the points. This is accomplished by turning the screw 11 and plotting continuously the apparent points of contact. Heretofore

it has not been possible on aerial photographs to determine points in the same vertical plane owing to the variable radial displacement of objects of different elevations.

Various changes may be made without departing from the spirit of the invention as claimed.

I claim as my invention:

1. A folding mirror stereoscope comprising: a supporting member, said member consisting of a vertical portion and an upper transverse portion; wings pivotally extending from said vertical portion adapted to provide a base; a pair of small mirror plates pivotally secured relative to the upper transverse portion and hingedly related one to the other; and a pair of large mirror plates pivotally mounted at the outer ends of said transverse portion, the parts being so arranged that the stereoscope may be folded into a compact package.

2. A folding mirror stereoscope comprising: a supporting member, said member consisting of a vertical portion and an upper transverse portion; wings pivotally extending from said vertical portion adapted to provide a base; a pair of small mirror plates pivotally secured relative to the upper transverse portion and hingedly related one to the other; a block secured to said supporting member and adapted to sustain said small mirror plates in extended position; and a pair of large mirror plates pivotally mounted at the outer ends of said transverse portion, the parts being so arranged that the stereoscope may be folded into a compact package.

3. A folding mirror stereoscope comprising: a supporting member, said member consisting of a vertical portion and an upper transverse portion; wings pivotally extending from said base portion adapted to provide a base; a pair of small mirror plates pivotally secured relative to the upper transverse portion and hingedly related one to the other; a block secured to said supporting member and adapted to sustain said small mirror plates in extended position; a pair of large mirror plates pivotally mounted at the outer ends of said transverse portion; and means for securing said large mirror plates in extended position, the parts being so arranged that the stereoscope may be folded into a compact package.

4. A folding mirror stereoscope comprising: a supporting member, said member consisting of a vertical portion and an upper transverse portion; wings pivotally extending from said vertical portion adapted to provide a base; a pair of small mirror plates pivotally secured relative to the upper transverse portion and hingedly related one to the other; a pair of large mirror plates pivotally mounted at the outer ends of said transverse portion; small mirrors on said

small mirror plates; and large mirrors on said large mirror plates, the parts being so arranged that the stereoscope may be folded into a compact package.

5. A folding mirror stereoscope comprising: a supporting member, said member consisting of a vertical portion and an upper transverse portion; wings pivotally extending from said base portion adapted to provide a base; a pair of small mirror plates pivotally secured to the upper transverse portion and hingedly related one to the other; a block pivotally secured relative to said supporting member and adapted to sustain said mirror plates in extended position at an angle one to the other; and a pair of large mirror plates pivotally mounted at the outer ends of said transverse portion, the parts being so arranged that the stereoscope may be folded into a compact package.

6. A folding mirror stereoscope comprising: a supporting member, said member consisting of a base portion and an upper transverse portion; a pair of small mirror plates pivotally secured relative to the upper transverse portion and hingedly related one to the other; a pair of large mirror plates pivotally mounted at the outer ends of said transverse portion; small mirrors on said small mirror plates; large mirrors on said large mirror plates; and means for adjusting certain of said mirrors relative to the other of said mirrors, the parts being so arranged that the stereoscope may be folded into a compact package.

7. A folding mirror stereoscope comprising: a supporting member, said member consisting of a base portion and an upper transverse portion; a pair of small mirror plates pivotally secured relative to the upper transverse portion and hingedly related one to the other; a pair of large mirror plates pivotally mounted at the outer ends of said transverse portion; small mirrors on said small mirror plates; large mirrors on said large mirror plates; and means adapted to raise and lower said small mirrors relative to said large mirrors, the parts being so arranged that the stereoscope may be folded into a compact package.

8. In a folding stereoscope of the four mirror reflector type: two pairs of mirrors, each of said pairs being adapted for use by one of the eyes of the observer; stop means for maintaining said mirrors in proper extended position to permit stereoscopic vision by the observer; and means for folding said mirrors into a compact package wherein the four mirrors are folded into parallel planes.

9. A folding mirror stereoscope comprising: a support comprising a substantially flat plate; primary and secondary pairs of mirrors; and means for attaching said mirrors to said support to permit movement thereof from an extended position in which said

mirrors are in stereoscopic relationship into a retracted position in which said mirrors lie close to said support in compact relationship therewith.

10. A folding mirror stereoscope comprising: a plane support; two pairs of mirrors; and means for operatively connecting said mirrors to said support to permit said mirrors to fold from stereoscopic relationship into planes parallel to the plane of said support.

11. A folding mirror stereoscope comprising: a support; and two pairs of mirrors hinged to said support in a manner to fold from stereoscopic relationship into parallel planes.

12. A folding mirror stereoscope comprising: a support; and two pairs of mirrors hinged to said support in a manner to fold from stereoscopic relationship into planes parallel to the plane of said support.

13. In a folding stereoscope, the combination of: a pair of mirrors; a support; means for hinging said mirrors relative to each other and relative to said support; and another pair of mirrors mounted in stereoscopic relationship with said first pair of mirrors when said first pair of mirrors is in extended position.

14. In a folding stereoscope, the combination of: a pair of mirrors; a support; hinge means on which said mirrors pivot to move into a given angular relationship with each other; auxiliary hinge means operating between said mirrors and said support to permit compact folding of said mirrors; and another pair of mirrors mounted in stereoscopic relationship with said first pair of mirrors when said first pair of mirrors is in extended position.

15. A folding mirror stereoscope comprising: a support having a pair of notches formed therein; a primary pair of mirrors; hinge means for retaining said mirrors in said notches when in retracted position, said hinge means permitting movement of said mirrors into retracted position; and a secondary pair of mirrors mounted to extend in stereoscopic relationship with said mirrors of said primary pair when said mirrors of said primary pair are in advanced position.

16. A folding mirror stereoscope comprising: a support; a primary pair of mirrors swingably mounted on said support to move from retracted position into an advanced position; a secondary pair of mirrors mounted on said support to move from retracted position into an advanced position wherein they are in stereoscopic relationship with the mirrors of said primary pair; and stop means for retaining the mirrors of said primary and secondary pairs in advanced position.

17. A folding mirror stereoscope comprising: a primary pair of mirrors; a secondary

- pair of mirrors disposed at a given angle relative to each other; and means for bodily moving said secondary pair of mirrors relative to said primary pair of mirrors without disturbing the angular relationship between the mirrors of said secondary pair. 5
18. A combination as defined in claim 17 including a hair-line support for mounting a pair of hair lines between said mirrors and the object being viewed. 10
19. In a folding stereoscope, the combination of: a plate; a hinge member pivoted to said plate on a given axis; a pair of mirrors pivoted to said hinge member on an axis perpendicular to said given axis; and means for determining the relative position of said mirrors on said hinge member. 15
20. In a folding stereoscope, the combination of: a plate; a hinge member pivoted to said plate on a given axis; a pair of mirrors pivoted to said hinge member on an axis perpendicular to said given axis; and means for determining both the position of said hinge member relative to said plate and the angular position of said mirrors relative to said hinge member. 25
21. In a folding stereoscope, the combination of: a plate; a hinge member pivoted to said plate on a given axis; a pair of mirror plates pivoted to said hinge member in a manner to contact said plate to which said hinge member is hinged; and means engaging said mirror plates to determine their angular relationship. 30
22. A combination as defined in claim 21 in which said means comprises a supporting block having a V-shaped edge engaged by said mirror plates. 35
23. A combination as defined in claim 21 in which said means comprises a supporting block hinged relative to said plate and having a V-shaped edge engaged by said mirror plates. 40
24. In a folding stereoscope, the combination of: a support; a plate; adjustable means for mounting said plate adjacent said support; a pair of mirrors foldably carried by said plate; and another pair of mirrors foldably carried by said support and extensible into stereoscopic relationship with said first-named pair of mirrors. 45
25. A folding mirror stereoscope comprising: a support foldable from a supporting position into a folded position in which said support lies substantially in a single plane; two pairs of mirrors; and means for mounting said pairs of mirrors relative to said support in swinging relationship therewith whereby the mirrors of one pair move into stereoscopic relationship with the mirrors of the other pair, said means permitting the folding of all of said mirrors in planes parallel to the plane of said support when in folded position. 55
26. A folding mirror stereoscope comprising: a support having a pair of notches formed therein; a primary pair of mirrors; hinge means for retaining said mirrors in said notches when in retracted position, said hinge means permitting movement of said mirrors into retracted position; and a secondary pair of mirrors hinged relative to said support in a manner to be moved from an extended position, in which they lie in stereoscopic relationship with said mirrors of said primary pair when said mirrors of said primary pair are in advanced position, into a retracted position in which said mirrors of said secondary pair lie parallel to the mirrors of said primary pair when in retracted position in said notches. 60
- In testimony whereof, I have hereunto set my hand at Los Angeles, California, this 30th day of April, 1925.
